(57) **CLAIM**

We claim the ornamental design for a digital rate calculating postage scale, as shown and described.

DESCRIPTION

FIG. 1 is a perspective view of a digital rate calculating postage scale according to the new design.

FIG. 2 is a top view of the scale shown in FIG. 1.

FIG. 3 is a bottom view of the scale shown in FIG. 1.

FIG. 4 is a side view of the scale shown in FIG. 1.

FIG. 5 is an opposite side view of the scale shown in FIG. 4.

FIG. 6 is a front view of the scale shown in FIG. 1; and, FIG. 7 is a back view of the scale shown in FIG. 1.

Features shown in broken lines in the drawings are not part of the claim.
